MUSICAL INSTRUMENT CONTROLLING
MEANS

Edmond Verlinden, Milwaukee, Wis.

Application May 13, 1933, Serial No. 670,821

7 Claims. (Cl. 84—123)

The invention relates to controlling means for automatic musical instruments such as organs and pianos.

An object of the invention is to provide simple, efficient and reliable means for controlling the playing, rereeling, replaying and stopping of the music sheet of an automatic musical instrument.

Another object of the invention is to provide an electromagnetically operated player control valve of simple and durable construction and capable of economical manufacture.

A further object of the invention is to provide a control system for a plurality of the valves whereby one or more of the valves are selectively movable to one position and the other or others simultaneously movable to another position.

The invention further consists in the several features hereinafter described and claimed.

In the accompanying drawing,

Fig. 1 is a schematic diagram of an automatic musical instrument embodying the controlling means of the invention;

Fig. 2 is a sectional elevation of a valve box showing one of the control valves of the invention;

Fig. 3 is a front elevation of the valve box, and Fig. 4 is a sectional view taken along the line 4—4 of Fig. 2.

In the drawing, the numeral 20 designates a tracker-box provided with a tracker-bar 21 over which a perforated music sheet 22 is drawn from a music spool 23 onto a take-up spool 24. The movement of the music sheet is effected by means of a suction-operated motor 25 acting through a transmission mechanism 26, both of well known construction. To effect playing, the take-up spool 24 is rotated to draw the music sheet forward over the tracker-bar; and to effect rereeling, the music roll is rotated in the opposite direction at a higher speed. The transmission also has a neutral position, so that when desired the music sheet and operating spools may be held stationary; and the usual braking means are provided in order that no slack will develop in the music sheet under operating conditions. The transmission mechanism includes a shifting lever 27 to the lower end of which is pivotally connected a shifting rod 28 actuated by pneumatic means, hereinafter described, for placing the transmission mechanism in a playing, rereeling or neutral position, as disclosed in my United States Letters Patent No. 1,874,663, issued August 30, 1932.

The transmission shifting means includes pneumatics 29, 30 and 31. The pneumatics 29 and 30 are mounted on opposite sides of a wedge-shaped

supporting block 32, while the pair of pneumatics 31 are mounted on opposite sides of a wedge-shaped supporting block 33 and are simultaneously operable. The supporting blocks 32 and 33 are provided with suitable ducts for applying suction to the pneumatics, as disclosed more fully in the above patent. The pneumatics 29, 30 and 31 carry fingers 37, 38 and 39, respectively, through the ends of which slidably passes the shifting rod 28, and each of these fingers carries an adjustable stop 40 engageable with the adjacent supporting block to limit the deflation of the associated pneumatic and correspondingly limit the travel of the shifting rod. The shifting rod has secured thereto a pair of spaced collars 41 and 42 adapted to be engaged by the fingers 37 and 38, respectively, and a pair of spaced collars 43 adapted to be engaged by the fingers 39.

As in the above patent, the ducts in the supporting blocks communicate with primary actions 44, 45, and 46 to control the application of suction to the pneumatics 29, 30, and 31, respectively.

A valve box 47 is provided for the selective control of the primary actions 44, 45, and 46 and includes a suitable casing 48. A valve board 49 is secured to a vertical wall of the casing and is connected by ducts 50, 51, and 52 with the respective primary actions 44, 45, and 46. The ducts 50, 51, and 52 terminate in spaced ports opening at the bottom surface of the valve board and controlled by disk valves 53, 54, and 55, respectively. Each disk valve is carried on a vertical valve stem 56 loosely and slidably fitting in a vertical guide bore 57 formed in the valve board, the upper end of the bore 57 being closed to insure against leakage.

The valves 53, 54, and 55 are movable to alternative open and closed positions by respective double-acting electromagnetic mechanisms 58, 59, and 60 mounted in the casing 48. Each mechanism comprises a rectangular frame 61 on which are carried a pair of spaced parallel selectively energized electromagnets 62 and 63. A T-shaped armature 64 has its leg portion between the electromagnets and pivotally supported on the frame by a pintle 65, and has its head portion adjacent the pole pieces of the electromagnets to be attracted in either direction. The part of the frame carrying the electromagnets and supporting the armature is preferably of magnetic material. The armature is held in its alternative positions by a spring-pressed toggle 66, and resilient stops 67 on the frame limit the maximum travel of the armature. Wiring terminals 68, 69, 55

and 10 are carried on the frame and connected with the electromagnets.

The free outer ends of the armatures project through a horizontal slot 71 in the front wall of the casing, and each is provided with a longitudinal open-ended slot or notch 72 to form a fork. The vertical valve stems 57 are received in the slots 72 of the respective armatures and each valve stem is screw-threaded for holding the disk valve and a pair of spaced leather nuts 73, the upper of which forms a lock nut for the valve. The slotted end of each armature is loosely mounted between the nuts 73 to move the valve to open or closed positions. The downward opening movement of the valve stems is adjustably limited by a padded stop bar 74 which is adjustably secured to the casing by screws 75 passing through vertical slots 76 in the opposite end portions of the bar. The valve board 49 is also vertically adjustable by attaching screws 75 passing through vertical slots 76 in the opposite end portions of the board.

The electromagnets 62 and 63 are momentarily energized, as hereinafter described, to operate the valves, and the valves are retained in open or closed positions by the spring-pressed toggle bars 66. In normal operation, only one of the three valves 53, 54, and 55 is open at any one time, the other two being closed. The ducts 50, 51, and 52 controlled by these valves are each under suction when the corresponding valve is closed, and the opening of the valves admits atmospheric pressure to the ducts to selectively operate the primary actions 44, 45, and 46.

For the manual control of the valve box 41 there are provided circuit-closers or push buttons 103, 104, and 105, respectively labeled "play", "neutral", and "reroll". The circuit-closers are disposed at any suitable location, and in some instances duplicate sets of the circuit-closers may be provided at different locations. The circuit-closers 103, 104, and 105 control respective electromagnetic relays 86, 87, and 88 of well-known construction disposed at any convenient location, and are connected with terminals of the electromagnets thereof by respective conductors 99, 100, and 101. The other terminals of these electromagnets are connected by a common conductor 97 with one terminal of a suitable source of current 98, and the other terminals of the circuit-closers are connected to the other terminal of the current source by a common conductor 101. Each relay includes a set or gang of contact members which are bridged when the relay is operated. One contact member of each relay is connected by a conductor 77 to one terminal of the current source 98, and a conductor 78 connects the other terminal of the current source with the common terminals of the electromagnets 62 and 63 of the valve mechanisms 58, 59, and 60. Conductors 79, 80, and 81 connect contact members of the relays 86, 87, and 88, respectively, with the "open" electromagnets 62 of the valve mechanisms 58, 59, and 59, respectively. Conductors 82 and 83 connect contact members of the relay 86 with the "closed" electromagnets 63 of the valve mechanisms 60 and 59, respectively. The conductors 82 and 83 also connect with contact members of the relays 88 and 87, respectively. A conductor 84 connects contact member of the relays 87 and 88 with the "closed" electromagnet 63 of the valve mechanism 58.

In addition to the manual control of relays 86, 87, and 88, these relays are also under automatic control for effecting the stopping, rerolling

and replaying of the music sheet. The tracker bar 21 is connected by a duct 108 normally under suction and adapted to be uncovered by a reroll perforation 109 in the music sheet for admitting atmospheric pressure to the duct. The duct 108 is connected to a primary action 110 of well known construction and the latter is connected by a duct 111 to a pneumatically operated circuit-closer 112 of well known construction. The circuit-closer includes a bank of contact members which are bridged when suction is applied to the device. One of the contact members is connected by a conductor 120 joining the conductor 107 leading to the current source 98, and another contact member is connected by a conductor 121 joining the conductor 101 leading to the electromagnet of the "reroll" relay 88. Other contact members may be connected by conductors 122 and 123 for controlling the "off" positions of combination and expression devices, not shown.

The take-up spool 24 is provided at one end with a pivoted trigger plate 127 which is movable outwardly when uncovered by the narrowed end of the music sheet, as in the above patent, into proximity with an arm of a rock-shaft 129 journalled in the side wall of the tracker-box. A stationary valve seat member 130 is arranged adjacent the outer end of the rock-shaft and is provided with one or more ports one of which is connected by a duct 131. A valve 132 is pivotally mounted on the valve seat member 130 and normally closes the ports, in which suction normally exists. The outer end of the rock-shaft is provided with an arm engageable with the valve 132 to open the ports and thus expose the ports to atmospheric pressure. This opening movement of the valve 132 is effected at the conclusion of the rerolling operation by the rock-shaft 129, which is engaged and swung by the then projecting trigger plate 127. When the take-up spool turns in playing direction, the trigger plate slides by the rock-shaft and is held at its inner position as soon as it is covered by the music sheet.

The duct 131 is connected to a two-way valve 133 by which it is placed in selective communication with other ducts 134 and 135, as in the above patent. The ducts 134 and 135 lead to different units of the primary action 110 which are connected by respective ducts 138 and 159 with respective pneumatically operated circuit-closers 140 and 160 of well known construction similar to the device 112. Each of the circuit-closers 140 and 160 includes a bank of contact members which are bridged when suction is applied, one contact member of each bank being connected to the current source conductor 120. Another contact member of the device 140 is connected by a conductor 154 joining the conductor 100 leading to the "neutral" relay 87, and another contact member of the device 160 is connected by a conductor 163 leading the "play" relay 86. The conductors 122 and 123 may also be connected with contact members of the circuit-closer 140.

In operation, a music sheet or roll is placed in the tracker-box and is hooked to the take-up spool 24 in the usual manner, the tracker transmission at this time being in neutral position. The operator then momentarily depresses the "play" circuit-closer 103, which establishes a circuit from the source of current 98, through the conductor 101, the circuit-closer 103, the conductor 99, the electromagnet of the relay 86, and the conductor 97 back to the source of current 75

When the relay 86 is thus operated, a circuit is established from the source of current 98, conductors 97 and 77, conductor 79, electromagnet 62 of the valve device 58, and conductor 78 back to the source of current. Simultaneously, other circuits are established by the relay 86 through the conductors 82 and 83, the electromagnets 63 of the valve devices 68 and 59, and the conductor 78. The energizing of the electromagnet 62 of the valve device 58 swings the armature 64 and pulls the disk valve 53 downwardly to open position, thus uncovering the port for the duct 50. The energizing of the electromagnets 63 of the valve devices 68 and 59 similarly causes the disk valve 55 to move upwardly against the valve board to close the duct 52, the duct 51 being already closed by the disk valve 54. The opening of the valve 53 admits atmospheric pressure to the duct 50 and actuates the primary action 44 to apply suction to the "play" pneumatic 29. The deflation of the "play" pneumatic moves the shifting rod 28 to the right as viewed in Fig. 1 and swings the transmission lever 27 to playing position, the other pneumatics 30 and 31 being free to expand. The motor then drives the take-up spool 24 to effect the travel of the music sheet in playing direction.

At the conclusion of playing the perforation 109 in the music sheet registers with the duct 108 connected to the tracker-bar, thus admitting atmospheric pressure to the primary action 110 and operating the circuit-closer 112. A circuit is thus established from the source of current 98 through the conductors 107 and 120, the bridged contact members of the circuit-closer 112, conductors 121 and 101, electromagnet of the "reroll" relay 88 and conductor 97 back to the source of current. The relay 88 is thus operated and establishes a circuit including the conductor 81 and electromagnet 62 of the valve device 59 to move the disk valve 54 to open position. Other circuits are simultaneously established by the relay 88 through the conductors 84 and 82 and electromagnets 63 of the valve devices 58 and 60 to close the disk valve 53, the disk valve 55 being already closed. The opening of the valve 54 admits atmospheric pressure to the duct 51 and actuates the primary action 45 to apply suction to the "reroll" pneumatic 30. The deflation of the "reroll" pneumatic shifts the transmission to "reroll" position, whereupon the music sheet is rewound onto the music spool 23. The pneumatically operated "reroll" circuit-closer 112 may also establish branch circuits through the conductors 122 and 123 to control combination and expression devices, not shown, which are thereby rendered ineffective during the rerolling operation. The circuit through electromagnet of the "reroll" relay 88 may also be established through the manually operated circuit-closer 105, and this may be done at any point in the playing operation.

At the conclusion of rerolling, the convergent or narrowed end of the music sheet exposes the trigger plate 127 on the take-up spool and permits the plate to move outwardly for swinging the rock-shaft 129, which lifts the valve 132 and opens the duct 131 to atmosphere. If the "stop-replay" valve 136 is placed in "stop" position, the duct 131 communicates with the duct 134 to admit atmospheric pressure to the latter duct for operating a unit of the primary action 110. By way of the duct 139 suction is applied to the circuit-closer 140, causing the contact members thereof to be bridged and a circuit established from the source of current 98, conductors 107 and 120, the bridge contact members, conductors 154 and 100, the electromagnet of the "neutral" relay 87 and conductor 97 back to the source of current. The relay 87 establishes a circuit including the conductor 83 and electromagnet 62 of the valve device 68, opening the valve 55. Other circuits are established including the conductors 84 and 83 and electromagnets 63 of the valve devices 58 and 59, closing the valve 54, the valve 55 being already closed. The opening of the valve 55 admits atmospheric pressure to the duct 52 and actuates the primary action 46 to apply suction to the "neutral" pneumatics 31. The deflection of these pneumatics shifts the transmission to "neutral" position, whereupon the music sheet is held stationary and creeping of the transmission is avoided. The abutment of the trigger plate 127 on the take-up spool with the rock-shaft 129, stops the rotation of the take-up spool so that the music sheet will not become unhooked from the spool. The "neutral" position of the transmission may also be obtained at any point in the travel of the music sheet by the manually operated "neutral" circuit-closer 104.

If automatic replaying of the music sheet is desired, the "stop-replay" valve 136 is moved to "replay" position when the music sheet is installed or at any time prior to the conclusion of rerolling. The opening of the valve 132 by the trigger plate then admits atmospheric pressure into the duct 133 to operate the corresponding unit of the primary action 110 through which suction is applied to the circuit-closer 106 by way of the duct 139. The circuit-closer 106 establishes a circuit from the source of current 98, conductors 107 and 129, bridged contacts of the circuit-closer, conductors 108 and 99, electromagnet of the "play" relay 26, and conductor 97 back to the source of current. The relay 26 then places the transmission to "play" position in a manner previously described.

In the event that all three of the adjacent circuit-closers 103, 104, and 105 are simultaneously depressed through carelessness or inadvertence, no damage will result, and the last circuit-closer released will determine the operative position of the transmission. The valve devices 58, 59, and 60 operate quickly and positively, so as to insure prompt action with short momentary contacts at the several circuit-closers. The valve devices are also capable of use with other musical instrument controls, and it is obvious that one or more of the devices may be actuated to one position while the remaining one or ones are actuated to the other position.

What I claim as new and desire to secure by Letters Patent is:

1. The combination of a tracker-box transmission, pneumatically operated devices for shifting said transmission to playing and rerolling positions, a control valve for each of said devices, a pair of electromagnets for each valve to move the valve to alternative positions, and electric circuit means for selectively energizing the electromagnets of one valve and for simultaneously energizing the opposed electromagnet of the other valve, said means including circuit-closing devices for the respective valves, each circuit-closing device having a circuit connection with one electromagnet of the respective valve and with the opposed electromagnet of the other valve.

2. The combination of a tracker-box transmission, pneumatically operated devices for

- shifting said transmission to playing and rerolling positions, a control valve for each of said devices, double-acting electromagnetic means for each valve to move the valve to alternative positions, and electric circuit means for energizing the electromagnetic means of each valve in selective opposite senses and for simultaneously energizing the other electromagnetic means in the other sense, said electric circuit means including circuit-closing devices for the respective valves, each circuit-closing device having an electrical connection with the electromagnetic means of both valves to effect the opposed movements of said valves.
3. The combination of a tracker-box transmission, pneumatically operated devices for shifting said transmission to playing and rerolling positions, a control valve for each of said devices, a pair of electromagnets for each valve to move the valve to alternative positions, a relay for each valve, circuit means for selectively operating said relays, and electric circuit means controlled by said relays for selectively energizing the electromagnets of one valve and for simultaneously energizing the opposed electromagnet of the other valve, each relay having a circuit connection with one electromagnet of the respective valve and with the opposed electromagnet of the other valve.
4. The combination of a plurality of valves each movable to alternative positions, double-acting electromagnetic means for each valve to move the valve to said alternative positions, and electric circuit means for energizing the electromagnetic means of at least one valve in selective opposite senses and for simultaneously energizing the other electromagnetic means in the other sense, said electric circuit means including circuit-closing devices for the respective valves, each circuit-closing device having an electrical connection with the electromagnetic means of both valves to effect the opposed movements of said valves.

nection with the electromagnetic means of both valves to effect the opposed movement of said valves.

5. The combination of a double-acting electromagnetic mechanism having an armature movable to opposite positions, a valve body having a valve seat and having a port and a laterally adjacent bore opening at said valve seat, and a valve engageable with said valve seat to cover said port and having a valve stem slidably guided in said bore and connected with said armature for moving the valve to alternative positions closing or exposing said port, said valve when engaging said seat closing both said port and bore.

6. The combination of a double-acting electromagnetic mechanism having an armature movable to opposite positions, a valve body having a valve seat and having a port and a laterally adjacent bore both opening at said valve seat, said bore extending perpendicularly to said seat and having a closed inner end, a valve engageable with said valve seat to cover said port and bore and having a valve stem slidably guided in said bore, said valve stem being connected with said armature for moving the valve to alternative positions closing or exposing said port.

7. The combination of a plurality of at least three valve means each movable to alternative positions, a pair of electromagnets for each valve means to move the means to alternative positions, and electric circuit means for energizing said electromagnets and including a plurality of circuit-closing devices, each device having an electrical connection with one of the electromagnets of at least one valve means and with the opposed electromagnets of the other valve means.

EDMOND VERLINDEN. 40
